UNITED STATES PATENT OFFICE.

HARRY W. STONE, OF BROOKLYN, NEW YORK.

DIRECTORY ATTACHMENT.

No. 823,559.

Specification of Letters Patent.

Patented June 19, 1903.

Application filed June 10, 1904. Serial No. 211,922.

To all whom it may concern:

Be it known that I, HARRY W. STONE, a citizen of the United States, residing at Brooklyn, in the county of Kings and State of New York, have invented an Improvement in Directory Attachments, of which the following description, in connection with the accompanying drawings, is a specification, like letters on the drawings representing like parts.

10 The object of this invention is to provide a convenient form of directory for telephones which may be readily attached to and removed from a telephone instrument.

15 The character and scope of the invention will be clearly apparent from a description of one particular form thereof illustrated in the accompanying drawings, in which—

Figure 1 represents a telephone desk instrument having the invention attached thereto. Fig. 2 is a plan view of the attachment. Fig. 3 is a detail view of the directory-supporting frame, and Fig. 4 is a detail of the directory-holding means.

20 In the particular embodiment of the invention herein selected for illustration the attachment comprises a suitable body *a*, having at any convenient point thereof means, such as a clamp *b*, for attaching the same to a telephone instrument. The clamp may be of any desired construction, but as here shown comprises a hooked member *b*, formed upon a laterally-extended portion *a'* of the body *a* and curved to fit the standard of a telephone desk instrument. Upon the threaded extremity *b'* of the curved portion *b* is mounted an adjustable clamping member *c*, consisting preferably, of a curved plate provided at one extremity with an aperture, as *c'*, Fig. 1, to fit loosely over the extremity *b'*, and at its opposite end with locking-lugs *c''*, adapted to engage suitable locking-recesses *b''* in the lateral extension *a'* of the body *a*. A suitable nut *b''* serves to effect the clamping action of the plate *c*. If desired, a suitable washer or 35 guard member *d*, preferably in the form of a strip of leather perforated at one extremity to fit over the extremity *b'*, may be employed to serve as a protection or guard against abrasion of the telephone instrument by the 40 clamping member.

The supporting frame or table upon which the directory element rests may be formed in any desired manner, but as here shown comprises the rectangular frame *a''*, formed by suitably bending the metal rod of which the body *a* is composed, the extremity of the rod

being secured to the body thereof, as at *a''*, by soldering or other suitable means. The frame or table *a''* is preferably slightly inclined from the horizontal to facilitate inspection of the directory. At one side of the supporting-frame, near the top or above the pivot-point, is provided a suitable stop or pin *e* which forms an abutment for the indexed elements of the directory proper and against which they may rest when in normal position.

60 The directory proper preferably comprises a series of cards *f* of convenient size to rest upon the support or table *a''* and provided with a thumb-index, preferably at the right side thereof, and upon each of these cards are arranged alphabetically the names of frequent users of the telephone. The directory-cards may be mounted upon the supporting-frame *a''* in any desired manner, but preferably they are pivoted at a convenient point, as upon an upright pin or standard *g*, which projects from the frame and passes through perforations in the cards. A clamp-nut *g'* and washer *g''* serve to retain the cards upon the standard *g*, and by tightening the nut the cards may be clamped sufficiently to prevent their turning from normal position of their own weight. While the pivot-point of the directory elements is here shown at the lower 70 right-hand corner thereof, it is obvious that the same may be located at any other convenient point, and the abutment pin or stop *e* may then be located correspondingly at a suitable point relative thereto. The body 75 portion of the attachment here shown is composed of a metal rod bent to suitable shape; but it is obvious that the same may be formed of any other suitable material and in any desired manner.

80 In placing the attachment in position the clamp-plate is removed from the threaded end of the clamping member *b*, and said member is then placed around the standard of the telephone instrument, the protector or guard *d* having been first interposed between the part *b* and instrument. The plate *c* is then replaced upon the threaded end *b'* and is forced to clamping position by means of the nut *b''*. Any one using the telephone and 85 wishing to ascertain a number places the finger upon the proper alphabetical letter and pressing down thereon holds the card and all below it against movement and with the other fingers of the same or other hand 90 swings the cards above it around to the left, as shown in Fig. 2, about the pivot *g*, thus ex- 95

100 105 110

posing the alphabetical list containing the several names and numbers. Having ascertained the desired number, a single movement of the fingers returns all the cards to 5 original position.

Many changes may be made in the construction and relative arrangement of parts without departing from the spirit and scope of the invention.

10 I claim—

1. A directory attachment for a telephone instrument comprising a supporting-arm provided with means for removable attachment to said instrument, a supporting-frame carried by said arm, a plurality of superposed directory elements pivoted at the bottom of their outer edges to the outer edge of said frame, and a stop also on the outer edge of said frame above the pivotal point of said 15 elements whereby said elements may be swung toward the instrument in consulting 20

the directory, and returned to normal position against said stop.

2. A directory attachment for a telephone instrument comprising a support adapted to be attached to said instrument, a plurality of superposed directory elements pivoted at their lower outer edges to the outer edge of said support, a stop on the outer edge of said support and above the pivotal point of said 25 elements, whereby said elements may be swung toward the instrument in consulting the directory and returned to normal position against said stop.

In testimony whereof I have signed my 30 name to this specification in the presence of two subscribing witnesses.

HARRY W. STONE.
